UNITED STATES PATENT OFFICE

WILLIAM C. KENNEY, OF CRANSTON, RHODE ISLAND, ASSIGNOR TO KENNEY MANUFACTURING COMPANY, OF CRANSTON, RHODE ISLAND, A CORPORATION OF RHODE ISLAND

CURTAIN FIXTURE

Application filed May 14, 1928. Serial No. 277,457.

In the development of brackets for window hangings, the recurrence of the fashion of multiple drapes has demanded the adaptation of single drape improvements to meet 5 the multiple drape requirements of the day.

The current standard popular curtain rod has for some time been typified by sheet metal members slidably engaged and having their free ends bent in to substantially 90° 10 to engage a wall bracket. This engagement is generally telescopic and is desirably so as the standard type of popular curtain rod by reason of its rolled edge is essentially tubular, although its edges do not meet on 15 the inner face.

With the recurrence of fashion in multiple drapes, the desire has been to readapt the brackets current at the previous period of this fashion so as to utilize the standard 20 popular type of extension curtain rod to which the public has become accustomed and which it has learned to buy through popular price distribution. This has been variously accomplished with varying degrees of success but in my present invention, I have 25 provided for a rod and bracket embodying generally the old standard principles with the more modern type of curtain rod. While well adapted for use with a rod of the bent end type, my bracket, however, may 30 be used with equal success with straight rods. For the purposes of this application, I have shown it only in connection with elbow rods, but it will be understood that 35 this treatment is purely illustrative and in no way limiting. Brackets in accordance with my invention may be used with either straight or bent end rods, and with rolled edge, tubular, or other rods.

The problem in such brackets is one of structural strength with economy in manufacture so that the more offset rod or rods in a plural rod equipment may be firmly supported even though spaced at a farther distance from the wall.

A rod and bracket as constructed in accordance with my present invention is illustrated in the accompanying drawings. In 50 these drawings:

Fig. 1 is a plan view of the end portions of a pair of rods mounted on a bracket.

Fig. 2 is a view on the line 2—2 of Fig. 1.

Fig. 3 is a similar section on the line 3—3 of Fig. 1. 55

Fig. 4 is a view of the bracket with the rods removed.

Fig. 5 is a triple bracket of the same type.

Fig. 6 is a view of one of the extension or connector pieces removed. 60

Fig. 7 is a tubular form of the same.

Figs. 8 and 9 are a pair of views showing face and edge views of a single bracket projection of the general type shown in Figs. 1 to 6, but with the old style locking lip, 65 and

Fig. 10 is a sectional detail of tubular arm assembly on base.

In the drawings, I have indicated at 1 the usual extension curtain rod member 70 which is an incomplete oval in cross sectioned and flattened down at 1¹ where it is bent to dispose the end 1² at right angles to the main portion of the rod. I preferably form these rods adjacent the free end with 75 an opening 1^a at top and bottom. These openings are not new but have usually been employed with a hooked bracket the point of the hook being thrust through these openings to support the rod. 80

In use with my wall bracket, these openings are adapted to receive resiliently projected catches 2^a which are yieldingly pressed through slots 3^b in a flattened tubular member 3 carried by the bracket plate 4. The portions 2^a are formed in the usual manner by a bend in a U shaped piece of spring stock 2 which, as shown in Fig. 3, may be thrust within the flattened tubular member 3 on the bracket 4. As shown in Fig. 3, the U shape of the member 2 is somewhat flattened at its bottom so as substantially to seat against the attaching plate 4 the projections 2^a projecting through the opening 3^b just enough to engage the openings 1^a in the rod and 1². 90

The members 3 may be conveniently provided with the usual stop shoulder as at 3¹ by a slit or dépression so that the inner end of the rod will have a definite stop where 95 100

so desired. Where a definite spacing is not so desired, this stop shoulder may be omitted and the rod end telescoped to any degree desired. When telescopic adjustment is desired, the rod may be provided with more than one set of apertures 1^a as indicated in Fig. 1.

The tubular construction of my extensions or coupling pieces 3 provides for the definite confinement of the spring or clip member 2 which, while in itself old, in the art combines very successfully with the flat tubular extension 3 into which it can be sprung in assembly and by which it is very completely protected in use.

The tubular structure of the member 3 also is of considerable advantage where it is desired to make such an extension as an independent unit as indicated in Fig. 10.

20 In such a case, a short upturned lip as at 4¹ in Fig. 10 receives the tubular member 3. This may be made a positive connection or a detachable connection as may be desired.

What I therefore claim and desire to 25 secure by Letters Patent is:

1. A curtain fixture, comprising a supporting bracket for a curtain rod, consisting of an attaching plate and a flat, rigid, elongated, substantially tubular projecting arm thereon, adapted to be telescopically engaged externally by the rod end and by which it is rigidly supported throughout substantially its entire telescopic engagement therewith, said arm having lateral apertures, the rod end having edge apertures, a spring clip having detent portions yieldingly projecting through the arm apertures and engageable with the apertured rod end when telescoped thereon.

40 2. In a supporting bracket for curtain rods having edge apertures, an attaching plate and a flat, rigid, elongated, substantially tubular projecting arm thereon, adapted to be telescopically engaged externally by the rod end and by which it is rigidly supported throughout substantially its entire telescopic engagement therewith, said arm having lateral apertures, a spring clip having detent portions yieldingly projecting through the arm apertures and engageable with the apertured rod end when telescoped thereon.

45 3. In a supporting bracket for hollow curtain rods, an attaching plate and a rigid, elongated, tubular projecting laterally apertured arm thereon, adapted to be telescopically engaged externally by the rod end and by which it is rigidly supported throughout substantially its entire telescopic engagement therewith, the arm having an internal spring member, projectable through its lateral apertures to engage the rod end.

50 4. In a supporting bracket for curtain rods, an attaching plate, and a rod-engaging arm projecting therefrom and consisting of 55 a member folded upon itself to provide a

flat rigid elongated substantially tubular sleeve over which a curtain rod end is adapted telescopically to engage and by which it is rigidly supported throughout substantially its entire telescopic engagement therewith, the overfolded edges of said sleeve constituting spaced parallel bearings for the rod end and themselves being apertured, and a spring confined within said sleeve and having detent portions yieldingly projecting through the apertures of the sleeve for engagement with the rod end.

5. In a supporting bracket for curtain rods, an attaching plate, and a rod-engaging arm projecting therefrom and consisting of a member formed to provide a flat rigid elongated substantially tubular sleeve over which a curtain rod end is adapted telescopically to engage and by which it is rigidly supported throughout substantially its entire telescopic engagement therewith, the lateral edges of said sleeve being apertured, and a spring confined within said sleeve and presenting a bow portion substantially sealed on said attaching plate and detent portions yieldingly projecting through the apertures of said sleeve for engagement with the rod end.

In testimony whereof I affix my signature.

WM. C. KENNEY.
